UNITED STATES PATENT OFFICE.

JOHN V. ALLEN, OF SOUTH WEYMOUTH, AND EDWARD E. ORR, OF WEYMOUTH, MASSACHUSETTS, ASSIGNEES TO UNITED SHOE MACHINERY COMPANY, OF PATERSON, NEW JERSEY, A CORPORATION OF NEW JERSEY.

SEWING-MACHINE.

1,213,788.

Specification of Letters Patent. Patented Jan. 23, 1917.

Application filed November 14, 1914. Serial No. 872,119.

To all whom it may concern:

Be it known that we, JOHN V. ALLEN and EDWARD E. ORR, citizens of the United States, residing at South Weymouth and Weymouth, respectively, in the county of Norfolk and Commonwealth of Massachusetts, have invented certain new and useful Improvements in Sewing-Machines; and we hereby declare the following to be a full, clear, and exact description of the invention, such as will enable others skilled in the art to which it appertains to make and use the same.

This invention relates to sewing machines of the type which employ a four-motion work feeding device by which the work is carried forward step by step.

More particularly the invention relates to an improved mechanism one purpose of which is to prevent the feed foot of the four-motion feeding mechanism from engaging the presser foot when the machine is running without work.

In mechanisms used heretofore for preventing the feed foot from engaging the presser foot, when the machine is running without work, for instance that illustrated in Letters Patent of the United States to Albert E. Johnson No. 1,089,473, dated March 10, 1914, the stop forming one of the elements of the mechanism has only a vertical movement and is engaged by a feed bar which has one movement at substantially a right angle thereto. In such a construction it has been found that the rubbing or drag of the stop on the feed bar racks the whole head of the machine and especially the vertically movable presser foot bar which carries the stop. This constant racking causes the bar to wear fast and destroys its bearings. Further, after the bearings have become worn the stitching mechanism is interfered with, thus causing the thread to break. In some special work, for instance securing together the two flaps of an insole as described in said Johnson patent, this strain is doubly injurious as the side strain on the presser foot bar is continual, the rubbing of the feeding device past the stop occurring at each feed movement, whether or not work is in the machine.

The object of the present invention is to improve the mechanism for the purpose re-

ferred to heretofore used by providing means for preventing wear and strain on 55 the presser foot bar and other machine parts.

In accordance with this object the invention contemplates the provision of a wear plate which partakes in the vertical movement of the feed bar but is held against longitudinal movement therewith. One form of such plate may be a lever, the active end of which has a long radius of movement and which is interposed between the stop on the presser foot bar and the feed foot bar. In 60 the preferred form of the invention the usual four-motion feed bar contacts with the lower face of the lever near its free end and the stop on the presser foot bar engages the upper face of the lever at a point substantially opposite its point of contact with the feed bar. By this means the wear and thrust due to the feeding and return strokes of the feed bar is absorbed by the lever and the thrust on the stop is in a vertical direction 65 only caused by the rise and fall of the lever as the feed bar rises and falls. All side strain on the bearings of the presser foot bar is thus eliminated. The lever is conveniently made of two vertically adjustable parts to 70 accurately fit it in the machine for the particular class of work being operated upon.

To the accomplishment of the above object and such others as may hereinafter appear, the invention comprises the devices, 85 combinations and arrangements of parts hereinafter described and particularly pointed out in the appended claims.

The preferred form of invention is illustrated in the accompanying drawings in 90 which:

Figure 1 is an end elevation of a Wilcox and Gibbs domestic machine equipped for securing together the two contiguous flaps of an insole, in accordance with the disclosure in said Johnson patent hereinbefore referred to, having also the present improved mechanism fitted thereto, and Fig. 2 is a detail view showing an end elevation of the improved mechanism and a portion of the 95 feed bar in their relation when the work has just been placed in the machine and the feed foot is about to rise to engage the work prior to the feed.

In the embodiment of the invention illustrated in the drawings the sewing machine

there shown is provided with the usual stitch forming mechanism including a straight, eye-pointed needle 2 and a rotary thread hook or cast off 4. The thread hook is rotated by being mounted directly upon the driving shaft 6 and the needle bar is reciprocated in guides on the frame by the oscillations of a pivotally mounted lever 8. A four-motion feed mechanism including a feed bar 12 pivoted at 14 to the machine frame, is operated by an eccentric 16 on the end of the driving shaft. The feed bar 12 is provided with an extension 13 for guiding its movements, said extension being held to the machine frame by a washer 15.

The work table 24 is removably held in a casting 25 with its front edge slightly in advance of the path of operation of the needle 2. In operating upon insoles the edge 20 flap of the insole, in working position, rests upon the work table, which presses well into the shoulder at the base of the feather, and the channel flap is pressed upon by the presser foot 18. A portion of the two flaps 25 of an insole in working position during the feed is illustrated in Fig. 1.

The small area of the work table in the illustrated machine leaves the thread hook 4 exposed and, owing to the position of the insole in the machine unless some protection be provided, the thread hook in its rotation, is liable to injure either the marginal portion of the sole by engagement therewith or the hand of the operator who directs the feed 35 of the work through the machine. To prevent such injury, the thread hook is covered with a cap or guard 28 which is supported on the casting 25. The guard 28 effectively houses the thread hook and shields the work 40 and also the operative.

In order to maintain the two flaps of the insole in stitch receiving position during the operation of the stitch forming mechanism, the machine is also provided with a work 45 positioning device or guide roll (not shown) mounted on the end of the arm 32 of a bell-crank lever 32-36 which is pivoted at 35. This guide exerts a pressure on the unchanneled surface of the insole opposite the 50 flaps, through the medium of the spring 37. The other arm 36 of the bell crank lever which supports the work guide is connected with a second bell-crank lever 38 which in turn is connected with a lever 44.

55 As the presser foot 18 must be lifted before the work can readily be removed from the machine, the lever 44 is provided to engage a shoulder 46 on the lower end of the presser foot bar 20. Also the bell-crank 60 lever 38 is connected to a treadle so that by the depression of the treadle, the lever 44 contacts with the shoulder 46 and raises the presser foot 18. Simultaneously with the raising of the presser foot the guide roll, 65 connected to the bell-crank lever 32-36, is

removed from the insole and thus the presser foot and guide roll are opened up to remove or insert work into the machine.

The features of the illustrated machine relating to stitching the two flaps together, 70 the device to hold the insole in stitch receiving position, and the mechanism for opening up said device to receive or remove the insole are not claimed herein as they are fully described and claimed in said Johnson patent hereinbefore referred to. 75

Referring now more particularly to the novel feature forming the subject matter of the present invention it is seen that in distinction from said Johnson patent 80 the machine is provided with a thrust absorbing lever 21 which is pivoted to the machine frame at 19. This lever, which is in the form of a flat plate, is mounted above the feed bar 12 and has a lug 26 on its under face at its free or active end which rests upon the upper face of the feed bar. By means of this construction the movement of the feed bar in its elliptical path causes the lever to oscillate slightly about its pivot 90 19 as a center. The radius of movement of the end of the lever where the lug 26 is located is so long compared to the amount of vertical movement imparted by the feed bar that the free end of the lever is caused to 95 move in a path substantially parallel to the axis of the presser foot bar. The lever 21 may therefore be correctly termed an absolute thrust-absorbing lever as it wholly prevents any side thrust from the feed bar being 100 transmitted to the presser foot bar.

The lever 21 is preferably bifurcated having the upper and lower arms 30 and 31. The arm 31 carries the lug 26 upon its end. The arm 30 is attached at one end to the 105 arm 31 by set screws 23 and carries near its free end an adjustable set screw 27 which is threaded through the arm and because of the resilience of the arm permits of its adjustment relative to the arm 31. This adjustment is provided to care for different thicknesses of work to be operated upon and to govern the relation of the feed foot to the presser foot. 110

The presser foot bar 20 is mounted, as 115 usual, in bearings in the frame 65 and carries the presser foot 18 at its lower end. This presser foot is held down upon the work by a spring 62 mounted upon the frame and bearing upon a loose wear collar 120 63 which rests on the usual fixed collar 64 on the presser foot bar. Extending downwardly from the presser foot 18 is a stop 56 which is adapted to engage the free end of the arm 30 on the lever 21. Thus the rise 125 and fall of the end of the lever 21 in its substantially vertical path will cause the stop 56, engaged by the lever, to impart a vertical movement only to the presser foot bar 20. By virtue of this construction there 130

is no strain on the presser foot bar at right angles to its axis and the side drag and thrust on the bearings of the bar resulting from the construction illustrated in said 5 Johnson patent are eliminated. The thrust due to the translation of the feed bar is all absorbed by the lever 21 at its lug 26 and bearing 19, and these parts may be suitably constructed of hardened material to provide for such strain.

10 In the operation of the machine the presser foot together with any other work clamping parts with which the machine may be provided is withdrawn by depressing the 15 treadle connected to the lever 38. The work is then placed in the machine and clamped between the presser foot and table by releasing the treadle. The thickness of the work raises the presser foot and stop 56 20 from their normal positions when no work is in the machine and places the spring 62 under compression. This position is shown by Fig. 2. The stitch forming mechanism is thrown into operation and the four-motion feed device carries the work forward after 25 each stitch is formed. After the feed foot has risen to grip the work ready for the forward movement, the lever 21 is brought into engagement with the stop 56 (see Fig. 1) 30 and the continued upward movement of the feed bar to clear the work from the table, acts through the stop 56 to raise the presser foot at the same time. The pressure from the spring 62 is thus transmitted to the feed 35 bar and the work is allowed to go forward without undue friction. This position of the parts is shown in Fig. 1. The stitch forming mechanism operates continuously so that there are periods when there is no 40 work in the machine and at such time if it were not for the stop 56 the feed foot in rising would strike the presser foot which is then held against the table by its spring 62, and injure the machine.

45 It will be seen from Fig. 2 that when no work is in the machine, the rise of the feed bar will cause an engagement of the lever 21 with the stop 56 before the feed foot reaches the presser foot. It is thus seen that 50 the present construction contains all the advantages described in said Johnson patent hereinbefore referred to while at the same time relieving the presser foot bar from all side strain.

55 The nature and scope of the invention having been indicated and its preferred embodiment specifically described, what is claimed as new, is:

1. A sewing machine, having, in combination, a presser foot bar, a presser foot on said bar, stitch forming mechanism, feeding means, means to actuate the feeding means, a stop mounted on the presser foot bar to control the movement of the presser foot, 60 and a thrust absorbing member between the

feeding means and stop arranged to absorb the thrust of the feeding means on the presser foot bar in the direction of feed.

2. A sewing machine, having, in combination, a four-motion feed device, a presser 70 foot bar, a presser foot mounted on the presser foot bar to co-act with the feeding device, and movable means mounted on the machine frame and actuated by the feeding device independently of the work to directly 75 transmit the vertical motion only of the feeding device to the presser foot.

3. A sewing machine having, in combination, work feeding means, mechanism to actuate the feeding means, a presser foot bar 80 mounted to reciprocate in a direction normal to the line of feed of the work, connections between the presser foot bar and the feeding means for lifting the presser foot bar during the advancing movement of the work, 85 and a thrust absorbing member included in said connections mounted independently of the presser foot bar which is constrained to move only in a direction to reciprocate the presser foot bar. 90

4. A sewing machine, having, in combination, a four-motion feeding means, means for operating the feeding means, a presser foot coöperating with the feeding means to clamp the work and movable in a direction 95 substantially normal to the direction of feed, a stop mounted on the presser foot bar and a lever pivoted to the machine frame, with a free end interposed between the presser foot stop and feeding means whereby the feeding 100 means acts through said lever to actuate the presser foot.

5. A sewing machine, having, in combination, a four-motion feeding means, means for operating the feeding means, a presser 105 foot coöperating with the feeding means to clamp the work and movable in a direction substantially normal to the direction of feed, a stop mounted on the presser foot bar, a lever pivoted to the machine frame with a 110 free end interposed between the presser foot stop and feeding means whereby the feeding means acts through said lever to actuate the presser foot, and means for adjusting said lever to vary its distance from the stop. 115

6. A sewing machine, having, in combination, a work feeding member, means to operate said member, a lever pivoted to the machine frame with its free end bifurcated and resting on the feeding member, an adjusting device for the bifurcated end of the lever, a presser foot coöperating with the feeding member, and a stop on the presser foot bar adapted to engage the free end of the lever. 120

7. A sewing machine having, in combination, stitch forming mechanism, a four-motion feeding device, a presser foot bar having means co-acting with the feeding device to thereby participate in the vertical move- 130

ment of the feeding device, a presser foot on said bar, and a thrust absorbing member interposed between said means and the feeding device, movably mounted independently of the presser foot bar to impart the vertical movement of the feeding device to the presser foot bar while fixed from participation in the longitudinal movement of the

feeding device to eliminate the thrust in the direction of feed from the presser foot bar. 10
